UNITED STATES PATENT OFFICE.

NATHAN CARLETON PHILLIPS, OF GLOUCESTER, MASSACHUSETTS, ASSIGNOR TO RUSSIA CEMENT COMPANY, OF GLOUCESTER, MASSACHUSETTS, A CORPORATION OF MASSACHUSETTS.

PACKAGE FOR LIQUID MATERIALS.

No. 926,855.

Specification of Letters Patent.

Patented June 29, 1909.

Application filed January 17, 1908. Serial No. 411,260.

To all whom it may concern:

Be it known that I, NATHAN CARLETON PHILLIPS, of Gloucester, in the county of Essex and State of Massachusetts, have invented certain new and useful Improvements in Packages for Liquid Materials, of which the following is a specification.

This invention relates to packages for liquid glue and similar materials, the package being composed of a tube of ductile metal, one end of which is provided with a suitable head having a contracted orifice for delivering the material when the tube is compressed, while the other end is left open until the tube has been charged or filled, and is then closed by pressing together the sides of the open end, and folding said sides to form flattened interlocked convolutions extending across one end of the package.

Heretofore the convolutions of the folded end have been held in place to maintain the closure, wholly by the stiffness of the metal, no means having been employed for positively uniting the convolutions, and preventing their separation. It has been found in some cases that the expansion of the charge contained in the package, has caused portions of the charge to displace or separate the convolutions, particularly at the end portions of the same, the result being the leakage of the material between the interlocked convolutions, and its appearance on the external surface of the package.

This invention has for its object to obviate this difficulty, and it consists in a package of the character above described, having the end portions of the convolutions of the folded end of the tube, united to prevent separation of said end portions, and the resulting leakage of the charge, the preferred union between the end portions of the convolutions being caps of solder, applied in such manner as to externally coat the exposed crevices at the ends of the convolutions, and bind the same together. The solder employed is preferably an alloy, having a low melting point, preferably not exceeding 212 degrees Fahrenheit, so that contact of the melted solder with the portions of the tube to which it is applied, will not melt said portions, and will not transmit sufficient heat to the interior of the package to volatilize the portions of the charge at the end where the closure is formed.

Of the accompanying drawings, forming a

part of this specification,—Figure 1 represents a perspective view of a ductile metal tube before its receiving or charging end has been closed. Figs. 2, 3 and 4 represent perspective views showing the successive steps employed in closing the receiving end of the tube. Figs. 5 and 6 represent side views on an enlarged scale showing the closed end of the tube before the application of the binding caps of solder. Figs. 7 and 8 represent views similar to 5 and 6 showing the solder caps in place. Fig. 9 represents a section on line 9—9 of Fig. 7. Fig. 10 represents a section on line 10—10 of Fig. 7, the scale of Figs. 9 and 10 being further enlarged.

The same numerals of reference indicate the same parts in all the figures.

In the drawings 12 represents a tube of ductile sheet metal, such as is commonly employed in making tubes to contain liquid and semi-liquid materials, such as liquid glue, the tube having a suitably formed head 13 at one end containing a discharge orifice through which the material is adapted to be forced by the compression of the body of the tube. The head 13 may be of any suitable construction, and as said head forms no part of my present invention, I will not describe the same in detail.

The tube is charged while the end opposite the head 13 is open, as shown in Fig. 1. After the charge has been inserted, the open end is flattened, as shown in Fig. 2, its sides being pressed together, and folded cross-wise, preferably along two lines, as indicated by Figs. 3 and 4, to form flattened interlocked convolutions 14, the length of which is greater than the diameter of the body of the tube, so that they project from opposite sides of the tube, as shown in Figs. 5 and 7. After the flattened end of the tube has been thus folded, a recess 15 exists between one side of the tube and the adjacent convolution of the folded end, as shown in Fig. 9, this recess being filled by the charge which the tube contains. It sometimes happens, especially when the charge is composed of liquid glue, that the expansion of the charge by changes in temperature, causes the charge to find its way along the crevice between the adjacent sides of the convolutions, and eventually escape at one or both ends of the convolutions. To prevent this leakage of the material is the object of my invention, which is carried out by uniting the end portions

of the convolutions in such manner as to prevent their separation, and the release of the contents of the tube, which may find its way into the crevice between the folded ends, 5 from the recess 15. This union between the end portions of the convolutions is preferably effected by applying caps 16 of solder to the end portions of the convolutions, said caps covering portions of the outer sides of 10 the external convolutions, and extending across the ends of the convolutions, as shown in Figs. 7, 8 and 10. The said solder caps may be conveniently applied by dipping the projecting end portions of the convolutions 15 into a body of melted solder, a sufficient quantity of solder being thus deposited upon the external surfaces of the immersed portions to form the caps 16.

The ductile metal or alloy of which the 20 tube 12 is made, besides being very thin, is liable to be melted at a temperature at which ordinary hard solder melts. To prevent melting of the material of the tube by its contact with the melted material which subsequently forms the solder cap 16, I make 25 the solder which forms said caps, of an alloy which melts at a relatively low temperature, preferably not exceeding 212 degrees Fahrenheit. I have found that by employing

an alloy of this character, I not only prevent 30 injury to the material of the tube which comes in contact with the alloy, but also prevent a transmission of sufficient heat from the solder through the walls of the tube to volatilize the adjacent parts of the charge 35 of the tube.

I claim:

A package composed of a tube of ductile metal provided with a suitable head at one end and flattened at the opposite end, the 40 sides of the flattened portion being pressed together, and folded to form flattened interlocked convolutions, the ends and portions of the sides of which are covered by solder caps which unite said end portions, and prevent separation thereof, the portions between said caps being left uncovered the solder comprising said caps being adapted to melt at a relatively low temperature, so that its application does not injuriously affect either the package or the contents 45 thereof.

In testimony whereof I have affixed my signature, in presence of two witnesses.

NATHAN CARLETON PHILLIPS.
